UNITED STATES PATENT OFFICE.

ERNEST S. FAIRBANKS, OF GREENFIELD, MASSACHUSETTS, ASSIGNOR TO STANDARD PRESSED STEEL CO., OF PHILADELPHIA, PENNSYLVANIA, A CORPORATION OF PENNSYLVANIA.

CLUTCH.

1,319,465.

Specification of Letters Patent.

Patented Oct. 21, 1919.

Application filed June 21, 1918. Serial No. 241,177.

To all whom it may concern:

Be it known that I, ERNEST S. FAIRBANKS, a citizen of the United States, residing in Greenfield, Franklin county, Massachusetts, have invented certain Improvements in Clutches, of which the following is a specification.

My invention relates to friction clutches of the type comprising a contractile and expandible ring disposed inside the rim of a loose pulley, which ring is adapted through suitable means to be placed in engagement with such pulley so that the latter will rotate with the shaft carrying the contractile and expandible ring.

My present invention is in the nature of improvements upon the structure disclosed in my Patent 1,186,301, June 6, 1916; and the object of my present invention is to increase the amount of contact between the ring and the surface of the pulley whereby a greater efficiency in operation may be secured, and on the other hand insuring evenness of wear.

A further object of my invention is to provide means whereby the ring constitutes a substantially floating member free to engage the walls of the pulley at substantially the same pressure at all points.

A further feature of my invention is to provide a structure that may be readily applied to line shafting already set up, or to any other type of shafting when the latter is installed.

These and other features of my invention are more fully described hereinafter, reference being had to the accompanying drawings, in which:

Figure 1, is a face view of my improved clutch.

Fig. 2, is a sectional view on the line II-II, Fig. 1.

Fig. 3, is a view similar to Fig. 1, illustrating a modified arrangement within the scope of my invention, and

Figs. 4 and 5, are views similar to Figs. 1 and 2, illustrating a further modification within the scope of my invention.

In the drawings, 1 represents a line- or counter-shaft, having a pulley 2 loose thereon; and 3 represents a hub keyed or otherwise secured to and rotating with the shaft

1. Disposed within the rim of the pulley and mounted so as to be out of contact there-

with when not in action, is a ring 4 forming the clutching member; which ring is operatively connected to the hub 3 and is provided with means hereinafter described whereby it may be expanded into engagement with the flange 5 of the pulley.

The hub carries a lever 6 disposed between suitable ear pieces 6^a and pivotally mounted on a pin 6^b carried by said ear pieces, and such lever coacts with a conical sliding collar 6^c of a type commonly employed as the actuating device of clutches.

Carried by the ring is a yoke-shaped member 7 connected to the ring 7^a, and having arms 7^b which, in the form of structure illustrated in Figs. 1 and 2, are disposed opposite apertured projections 8 carried by the hub, and are connected to said hub by means of bolts 9 placed in said apertured projections and secured to the yoke-shaped member by pins 10; the opposite ends of said pins 9 having heads or washers 11 in engagement with springs 12 which are preferably disposed in sockets 13 formed in the apertured members 8. These springs, when the ring is expanded into contact with the pulley flange, are under tension, and when the ring is released they serve to hold the same out of contact with said pulley flange.

Oppositely disposed with respect to the yoke member 7 is a yoke member 15 having arms 16; the ends of which are connected at 17 to links 18, whose opposite ends are secured at 19 to the free ends of the ring.

The arms of the yoke 15 are preferably reduced in thickness so as to render them resilient and deflectable one relatively to the other and both relatively to their connecting portion 20 which is engaged by the lever 6 for operating the clutch ring 4 through coaction with the conically sliding collar 6^c.

In the structure illustrated in Fig. 3, the hub is split and connected together by bolts 21 of usual type, while the apertured projections 8^a are carried by one half of the hub and are connected by bolts 9^a with the yoke member 7 in a manner substantially similar to the structure illustrated in Figs. 1 and 2, excepting that their relation is reversed, and the springs are adapted to sockets in said yoke member.

In order to take up wear which may occur upon the inner surface of the pulley or the outer surface of the split ring, in the form

of structure shown in Figs. 1, 2 and 3, the yoke member 15 is provided with a screw 22 having threaded engagement with one of the arms 16 and having its end arranged to 5 crowd or bear against the other arm 16 so that after such wear occurring between the engaging surfaces of the clutch ring and pulley flange, inward movement of said screw will increase the separation of the 10 arms of the yoke member and thereby increase the normal diameter of the split ring.

In Figs. 4 and 5, I have shown a further modification in which the connection between the clutch hub and the clutch ring is 15 slightly different from the structures illustrated in Figs. 1, 2 and 3. In the structure shown in Figs. 4 and 5, a single post connection is employed; the clutch ring carrying a projection or boss 25 recessed to receive the head of a bolt 9^b which is pinned 20 at 10^b to the hub, with a spring 12^a interposed between the head of said bolt and the socket or recess 13^a in the boss carried by the split ring. The free ends of the split 25 ring are connected together by an element 15^a with interposed links 18^a, and said member has a split portion with a conical seat 26 for the reception of a conical sleeve 27; 30 a screw 28 being employed to draw up said sleeve so as to regulate the extent of opening of the split portion of the yoke member 15^a in order that proper positioning of the clutch ring with reference to the flange of 35 the pulley can be insured to take up all wear that may occur. In other respects, the structure shown in Figs. 4 and 5, is substantially like the structure shown in Figs. 1, 2 and 3. If desired, a roller bearing may be employed with the pulley; the same being 40 inclosed within a case 29.

In manufacturing the improved structure forming the subject of my invention, the ring, hub and yoke member 7, of the form shown in Figs. 1, 2 and 3, as well as the 45 boss hub and ring of the structure shown in Figs. 4 and 5, are preferably cast in one piece. For operative purposes, it is necessary to cut the connection between the yoke and hub, and the space formed by such 50 cutting operation is filled in with washers 30, as illustrated in the several views. In addition, the part illustrated by dotted lines in Fig. 3, and preferably cast with the clutch ring, is subsequently broken out before the ring is finished for application to the pulley.

It will be understood, therefore, that the several forms of spring-supported connections between the clutch ring proper and the 60 hub, and as illustrated in the accompanying drawings, is such that the structure provides what may be termed a floating clutch ring; positive in its action, and engaging substantially the entire surface of the flange 65 of the pulley and one that is capable of being

readily thrown out of action so as to be supported by its hub entirely clear of such pulley surface.

It will be understood, of course, that changes may be made in the various details of construction without departing from my invention, and that while definite embodiments of my invention have been shown in the accompanying drawings and described with more or less particularity, I do not 75 wish to be limited to the constructions disclosed; desiring to claim broadly any construction capable of performing the functions for which my improved clutch structure has been designed. 80

I claim:

1. In a clutch, the combination of a pulley, a split ring for engagement with one flange of the same, means for expanding said split ring; said ring having a lateral 85 projection diametrically opposite the split portion of the same, a hub, and a resilient connection between the lateral projection of the split ring and said hub.

2. In a clutch, the combination of a pulley, a split ring for engagement with one flange of the same, means for expanding said split ring; said ring having a lateral projection diametrically opposite the split portion of the same, a hub, a resilient connection between the lateral projection of said split ring and the hub, and a resilient or flexible connection between the free ends of the split ring. 95

3. In a clutch, the combination of a pulley, a split ring for engagement with one flange of the same, a yoke member connecting the free ends of the ring, a hub, means carried thereby for expanding said split ring, a lateral projection carried by said 100 ring opposite the split portion thereof, and a spring connection between said projection and the hub.

4. In a clutch, the combination of a pulley, a split ring for engagement with one flange of the same, a yoke member connecting the free ends of the ring, a hub, means carried thereby for expanding said split ring, a lateral projection carried by said 11 ring opposite the split portion thereof, and a spring connection between said projection and the hub and disposed opposite said yoke member.

5. In a clutch, the combination of a pulley, a split ring for engagement with a flange of the same, a hub, a tension member, links connecting said tension member with the free ends of the split ring, a lever pivotally connected to the hub and adapted to engage said tension member to expand the 11 split ring, a lateral projection carried by said ring opposite the split portion thereof, and a resilient connection between said projection and the hub.

6. In a clutch, the combination of a pul- 1

ley, a split ring for engagement with a flange of the same, a tension member, links connecting said tension member with the free ends of the split ring, a split hub, means connecting the same together, a lever pivotally connected to one portion of the hub and adapted to engage said tension member to expand the split ring, a lateral projection carried by said ring opposite the split portion thereof, and a resilient connection between said projection and the hub.

7. In a clutch, the combination of a pulley, a split ring for engagement with a flange of the same, a hub, a tension member, links connecting said tension member with the free ends of the split ring, a lever pivotally connected to the hub and adapted to engage said tension member to expand the split ring and projecting laterally beyond the plane of the pulley, a yoke member carried by the ring, and springs connecting said yoke member and the hub.

8. The combination, in a friction clutch, of a shaft having a loose pulley thereon, a hub fixed on the shaft adjacent the pulley, a split clutch ring positioned inside the pulley rim, a lever pivoted to said hub, resilient or flexible means connecting the free ends of the split ring including a yoke mem-

ber in operative engagement with said lever, means for adjusting the position of the arms of said yoke member with respect to each other, a yoke arm connected to the ring opposite said yoke member; said yoke arm projecting laterally at the side of the clutch ring outside the plane of the pulley flange, and a flexible connection between said laterally projecting yoke arm and the hub.

9. The combination, in a friction clutch, of a shaft having a loose pulley thereon, a hub fixed on the shaft adjacent the pulley, a split clutch ring positioned inside the pulley rim, a lever pivoted to said hub, a pair of toggle links connected to the free ends of the split ring, a yoke member connected to said toggle links and in operative engagement with said lever, means for adjusting the position of the arms of said yoke member with respect to each other, a laterally projecting yoke arm connected to the ring opposite said yoke member, a bolt connecting said projecting yoke arm with the hub, and a spring in operative engagement with said bolt and forming a flexible connection between said projecting yoke arm and the hub.

ERNEST S. FAIRBANKS.
